PNEUMATIC PISTOL

Walter A. Tratsch, Chicago, Ill.

Application July 3, 1946, Serial No. 681,218

2 Claims. (Cl. 124—11)

1

This invention relates to certain new and useful improvements in pneumatic pistols, one especially adapted for target practice and designed to propel a pellet or other missile under pneumatic pressure in the direction of a target.

The invention contemplates an arrangement of parts for controlling the admission of air under pressure to the firing barrel in synchronism with an arrangement for controlling the individual movement of the shots or pellets from the shot tube to the firing barrel, and to this end this present invention has as one of its principal objects the provision for attaining the above accomplishments by mechanism which is simple in structure and economical in manufacture.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a part sectional elevational view of a pneumatic pistol embodying the invention;

Fig. 2 is a fragmentary top plan view of the same;

Fig. 3 is an enlarged sectional detail view taken substantially on line 3—3 of Fig. 1;

Fig. 4 is a fragmentary sectional detail view in elevation similar to Fig. 1, illustrating the parts in firing position;

Fig. 5 is a fragmentary sectional elevational view similar to Fig. 4, showing the parts locked against firing operation;

Fig. 6 is a fragmentary perspective view showing the manner of loading the shot in the shot barrel;

Fig. 7 is an elevational view of the reverse side of the pistol as viewed in Fig. 1;

Figs. 8 and 9 are enlarged perspective views illustrating the mechanism for closing the passage of the shot tube with respect to the firing tube of the pistol.

The drawings illustrate the preferred form of construction by which the several objects of the invention are accomplished.

In this connection my improved pneumatic pistol includes a handle structure 10 from which extends a barrel 11. In this barrel 11 there is arranged a firing tube 12 and a shot tube 13, arranged in substantially parallel relation with respect to each other and extending from a mounting block 14.

The mounting block 14 has formed therein a passage 15 communicating with an enlarged bore

2

16 in which is slidably arranged a valve plunger 17 functioning to normally close communication between the passage 15 and orifice 18, which orifice 18 is in turn normally closed by a second valve plunger 19. This plunger 19 is slidably mounted in the mounting block 14 and is provided with a hollow end portion 20, one wall of which provides an orifice 21 adapted to communicate with the orifice 18 so as to open communication between the passage 15 and the firing tube 12.

Communicating with this passage 15 is a nipple 22 to which a rubber hose or other flexible conductor may be connected for connecting the nipple 22 in communication with a suitable source 15 of compressed air.

As best shown in Fig. 1, the pellets or shots 23 contained within the shot tube 13 are adapted to be successively admitted to the firing tube 12 forwardly of the valve plunger 19 through the opening 24. To assure the admission of one shot at a time to the firing tube 12, a stop arrangement is provided. In this instance, this stop arrangement includes a stop finger 25 depending into the shot tube 13 a predetermined and sufficient distance to block the passage of pellets from the shot tube to the firing tube until this finger 25 is moved from such blocking position by means presently to be explained.

The valve plunger 19 has a head portion 26 providing an annular groove 27 into which engage the bifurcated end portions 28 of a lever 29 pivotally supported by means of a pintle 30 between the side walls 31 of the handle structure 10 and projected through an elongated slot 32 formed in a trigger 33. The trigger 33 provides a stud 33' which bears against a web 34' formed as an integral part of the lever 29 whereby upon pivotal movement of the trigger 33 in an anti-clockwise direction as viewed in Fig. 1, this stud 33' will bear against the web 34' to pivot the lever 29 to effect movement of the plunger 19. This trigger 33 is pivotally supported by a pintle 34 carried by the side walls 31 of the handle structure 10, and it includes a cam finger 35 which, as shown best in Fig. 3, is adapted to engage the end portion 36 of an arm 37. This arm 37 is formed as an integral part of a U-shaped bridge 38, and the arm 37 as well as its companion arm 39 is pivotally connected to the mounting block 14 as at 40. The stop finger 25 is formed as an integral part of this bridge portion 38.

The arrangement is such that when the trigger 33 is pivoted in an anti-clockwise or firing direction, the cam finger 35 will bear against the end portion 36 of the arm 37 and impart a pivotal

movement to the bridge portion 38 in a clockwise direction as viewed in Fig. 1, thereby to elevate the stop finger 25 to permit the movement of the next succeeding pellet or shot 23.

Simultaneously with this movement, the lever 29 will slide the valve plunger 19 forwardly in the direction of the barrel 11 to register the orifice 21 with the orifice 18, whereby to admit air under pressure to the firing tube 12 to project the pellet or shot 23 therefrom.

Air under pressure will be thus admitted through the orifices 18 and 21 when the valve plunger 17 is permitted to be moved rearwardly under air pressure through the passage 15, in a manner now to be explained.

This movement of the valve plunger 17 is permitted by the following described structure. Pivots connected by means of a pintle 41, is a rocker block 42 having a pair of spaced arms 43 between which a roller 44 is pivotally connected by means of the pintle 45. This rocker block 42 provides a U-shaped web 46 to provide spaced arms 47 and 48. The arm 48 has connected thereto, as at 49, one end portion of a spring 50, the opposite end portion of the spring 50 being connected as at 51 to the bottom wall 52 of the handle structure 10. The arm 47 of the rocker block 42 carries a pin 53 which engages a seat 54 formed in an arm 55 pivotally carried as at 56 by the rearwardly extending arm 57 formed as an integral part of the trigger 33. The arm 55 is normally urged in a direction to engage the pin 53 by means of a spring 58 connected as at 59 to the arm 55, and as at 60 to the trigger arm 57.

The arrangement is such that upon pivotal movement of the trigger 33 in an anticlockwise direction, the arm 55 will be caused to bear against the pin 53 and pivot the rocker block 42 in a clockwise direction as viewed in Fig. 1, to disengage the roller 44 from a blocking arm 61. During the firing operation the extension 17' of the plunger 17 will under pneumatic pressure forcefully pivot the arm 61 in an opposite direction to strike the end of the arm 61 against the extension 68 disengaging the arm 55 from the pin 53 thereby to allow the rocker block 42 to return to its normal position by the action of the spring 50, after the firing operation has been completed. This blocking arm 61 is pivotally carried by a pintle 62 between the side walls 31 of the handle structure 10. The lower end portion of the blocking arm 61 is bifurcated as at 63 and provides a shoulder 64 which is adapted to engage an end portion of a latch arm 65 pivotally carried by a pintle 66 between the side walls 31 of the handle structure 10. This latch arm 65 is normally held into position with the shoulder 64 by means of a spring 67 (Fig. 1). The latch arm 65 is disengaged from the shoulder 64 by the upward movement of the arm 55, which arm 55 carries a lateral extension 68 adapted to engage the latch arm 65 when moved upwardly to disengage the latch arm 65 from the shoulder 64. Upon this disengagement between the latch arm 65 and shoulder 64, the locking arm 61 will be free to pivot and consequently the air pressure in back of the valve plunger 17 will move the valve plunger 17 to the right as viewed in Fig. 1 to admit the air under pressure into the shot tube 12. When this free pivotal movement of the blocking finger 61 takes place, the shoulder 64 will be elevated in the position shown in Fig. 4, so that upon release of the trigger 33 for return to its normal position as shown in Fig. 1, the

rocker block 42 will be pivoted in snap action by action of the spring 50 and again dispose the blocking arm 61 in the position shown in Fig. 1, with the shoulder 64 in latched engagement with the latch arm 65.

In order to assure a full stroke of the trigger 33 in an anticlockwise direction, there is provided a full stroke device 69 comprising a ratchet head 70 and a pawl 71, the pawl being formed as an integral part of a rotatable disc 72 carried by a pin 73. This pin 73 is supported by a plate 75 positioned between the side walls 76 of the handle structure 10. Full stroke devices of this character have been used in connection with coin 15 slides of vending machines and are of well-known construction similar to that shown in Patent 881,688.

In Figs. 6 and 7, I have illustrated the manner of loading the shots in the shot tube 13. The shots 23 are packed in a suitable tubing 77 of a construction substantially similar to that shown in U. S. Letters Patent No. 2,297,947 and in a manner substantially shown and described in U. S. Letters Patent No. 2,339,064.

Formed on one of the side walls 31 of the handle structure 10 is an elongated tubular section 78 and slidably arranged in this tubular section 78 is a rod 79, one end of which supports a bracket structure 80 provided at its upper end portion with a tubular sleeve 81. The shot tube 13 has a rearwardly extending portion 82 which loosely extends through a split sleeve 83, the end of the shot tube being indicated at 84. In this end portion 84 of the shot tube 13, the tube 77 with the shots 23 therein is slidably projected.

Slidably carried by the sleeve 81 is a tube 85 and arranged within this tube 85 is a ram rod 86. This sleeve 81 and the tube 85 are normally pivoted in the position shown in Fig. 1, with the tube 85 telescopically arranged upon the end portion 82 of the shot tube 13. This tube 85 provides a finger latch 87 which has a finger button 88. When the tube 85 is in the position shown in Fig. 2, the latch finger 87 is pivoted downwardly to engage the upper end portion 89 of a locking bar 90 (Fig. 1).

To load the shots in the shot tube 13, the finger latch 87 is pivoted to a substantially vertical position or in a position where it will pass freely through the slot 90' of the sleeve 83, and after the tube 85 has been completely withdrawn from telescopic position upon the end portion 82 of the shot tube 13, the sleeve 81 is pivoted to the position shown in Fig. 6. This permits positioning the loaded tube 77 into the end portion 82 of the shot tube 13, after which the sleeve 81 is pivoted back to its normal position, the tube 85 moved forwardly to bear the ram rod 86 against the end portion 91 of the tube 77, whereby to pierce this end portion and move into the tube to force the shots from the tube 77 into the forward end portion of the shot tube 13 or in the position shown in Fig. 1. The tube 77 remains in the sleeve 82 after the shots are removed therefrom and is removed from the sleeve when the sleeve 81 and its associated parts are pivoted to the position shown in Fig. 6.

The lock bar 90 is pivotally carried by a pintle 91' carried by the adjacent side wall of the handle structure, and it is normally urged in the position shown at A (Fig. 4) by means of spring 92. This lock bar 90 has a lateral extension 93 formed on its lower end portion, and when in the position shown at A (Fig. 4), it will be disposed in the path of a depending finger 92'.

formed as an integral part of the trigger arm 57, and in this position of the extension 93, the trigger is prevented from returning to its normal or starting position as shown in Fig. 5. However, upon complete insertion of the tube 85 in telescopic position about the end portion 82 of the shot tube 13, the operator will pivot the finger latch 87 in a direction to bear such finger latch upon the upper end portion 89 of the lock bar 90, and in so doing the lock bar 90 will be pivoted in 10 to an anticlockwise direction about its pivot 91' to dispose the lateral extension 93 from the path of movement of the finger 92' of the trigger arm 57, to permit the trigger to complete its return to the position shown in Fig. 5.

Prior to the loading operation, the trigger is pivoted to firing position and manually held in such position until the extension 93 is disposed in the manner described, beneath the finger 92', the plunger 17 having returned by action of the rocker block 42 to closing position with respect to the orifice 18.

In order to prevent the admission of the compressed air into the shot tube 13 during the loading operation of the shots into the shot tube when the ram rod is in the position shown in Fig. 6, by the accidental pivotal movement of the trigger to firing position, I provide upon the shot tube 13 adjacent the orifice 24 a fixed sleeve 94 having a partially cut-out portion 95 into which projects a finger 96 carried by a rotatable sleeve 97 disposed between the tube 85 and the fixed sleeve 94 when the ram rod is in the position shown in Fig. 1. This rotatable sleeve 97 likewise has a cut-out portion 98 for the reception of a finger 99 formed as an integral part of the tube 85. A second cut-out portion 100 is provided in this sleeve 97 for the passage of the blocking finger 25. Formed in this rotatable sleeve 97 is an opening 101 which is adapted to register with the orifice 24 when the ram rod is in its innermost position and the finger latch 87 pivoted upon the upper end portion of the lock bar 90. However, when the finger latch 87 is pivoted in a direction to be positioned for movement through the slot 89' of the split sleeve 83, the extension 99 will, when the finger latch 87 is rotated, impart rotation to the sleeve 97 so as to pivot the sleeve 97 to a position to dispose the opening 101 thereof from registration with the orifice 24, and with a portion of the sleeve 97 blocking passage through the orifice 24. A spring element 102 has one end portion connected as at 103 to the rotatable sleeve 97 and an opposite end portion connected as at 104 to the shot tube 13, whereby to hold the sleeve 97 in position upon the shot tube 13 for rotation thereabout. In this manner, when the sleeve 97 is rotated in the position shown in Fig. 9, the orifice 24 will be closed by a wall of the sleeve 97 and thus prevent any compressed air from going into the shot tube during the loading operation, should the trigger be moved accidentally to firing position.

From the foregoing description, it will be apparent that I provide a pneumatic pistol in which the mechanism for controlling the feeding of shots from the shot tube to the firing tube is in complete synchronism with the operation of the mechanism for permitting the compressed air to be admitted into the firing tube for firing 70 purposes.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. In a pistol of the class described, a barrel 15 providing a firing tube and a shot tube in parallel relation with respect to each other and providing a normally open orifice through which the shot tube communicates with the firing tube and through which orifice shots pass from the shot tube to the firing tube, shot loading means for the shot tube, a movable sleeve on the shot tube and rotatable relative thereto and having a portion movable upon rotation of the sleeve relative to the shot tube to close said orifice, means actuated by operation of an element of the shot loading means for rotating the sleeve to move said portion into closing position with respect to the orifice during loading of shots by the shot loading means into the shot tube, means for controlling the passage of shots from the shot tube to the firing tube including trigger-actuated means, and a trigger pivotally associated with the barrel for actuating said trigger-actuated means.

2. In a pistol of the class described, a barrel 35 providing a firing tube and a shot tube in parallel relation with respect to each other and providing a normally open orifice through which the shot tube communicates with the firing tube and through which orifice shots pass from the shot tube to the firing tube, shot loading means for the shot tube, a movable sleeve on the shot tube and rotatable relative thereto and having a portion movable upon rotation of the sleeve relative to the shot tube to close said orifice, means actuated by operation of an element of the shot loading means for rotating the sleeve to move said portion into closing position with respect to the orifice during loading of shots by the shot loading means into the shot tube, means for controlling the passage of shots from the shot tube to the firing tube including trigger-actuated means, a trigger pivotally associated with the barrel for actuating said trigger-actuated means, and means actuated by the shot loading means for latching said trigger against operation during the loading of shots by said shot loading means into said shot tube.

WALTER A. TRATSCH.
